UNITED STATES PATENT OFFICE.

HAROLD ARTHUR MOREY AND CHRISTOPHER PHILIP ROBERTS WARREN, OF SAULT STE. MARIE, ONTARIO, CANADA.

PAPER-CORE BUNDLING DEVICE.

Application filed March 23, 1922. Serial No. 546,200.

To all whom it may concern:

Be it known that we, HAROLD ARTHUR MOREY and CHRISTOPHER PHILIP ROBERTS WARREN, both subjects of the King of Great Britain, and both residents of the city of Sault Ste. Marie, in the district of Algoma, in the Province of Ontario, Canada, have jointly invented certain new and useful Improvements in Paper-Core Bundling Devices, of which the following is the specification.

Our invention relates to improvements in paper core bundling devices and the object of the invention is to devise a simple means whereby a plurality of paper cores may, when bundled together, be held securely for shipment and such a device as may be easily and quickly applied with a minimum amount of labour and it consists essentially of the arrangement and construction of parts as hereinafter more particularly explained.

Fig. 1 is a side elevation of our paper core bundling device.

Fig. 2 is an enlarged plan view of our paper core bundling device.

Fig. 3 is a side elevation of the upper portion of our paper core bundling device as shown in Fig. 2.

Fig. 4 is a sectional plan view taken directly above the retaining plate.

Fig. 5 is a cross sectional detail through the retaining plate.

Fig. 6 is a sectional view on line 6—6, Fig. 2.

Fig. 7 is a plan view showing an alternative form of locking means.

Fig. 8 is an enlarged sectional detail through the locking means shown in Fig. 7.

In the drawings like characters of reference indicate corresponding parts in each figure.

1 indicates a series of paper cores forming a bundle. 2 and 3 are retaining plates. Each plate 2 and 3 has a rolled edge 4 and cupped portions 5 depending from the plate and fitting within the hollow centre of each core thereby holding the cores in their proper relative position and together. 6 are rectangular orifices formed in the inner edge of each of the exterior portions 5 as clearly indicated in Fig. 4. 7 and 7^x are bosses extending respectively from the upper and lower faces of the plates 2 and 3. 8, 9, 10 and 11 are levers. The levers 8 and 9 are pivoted

upon the boss 7. The levers 10 and 11 are pivoted upon the boss 7^x. The opposing ends of the levers 9 and 10 overlap and are pivotally connected together by a bolt or rivet 12. The opposing ends of the levers 11 and 8 are pivoted together by a bolt 13.

The ends of the levers 8 and 10 are provided with outturned extensions 14 and 15 having the ends 16 and 17 turned outward at right angles to the extensions and in which are formed orifices 18 and 19. The portion 17 is provided with a further extension portion 20 extending horizontally outward. 21 is a bolt extending through the orifices 18 and 19 and provided at one end with a squared head 22 against which the extension 20 bears so as to prevent it turning. 23 is a nut which is threaded upon the opposite end of the bolt. 24 and 25 are fingers extending downward from the ends of the lever extensions 14 and 15. The opposite end of the lever 8 is provided with an extension 26 from which depends a finger 27. The corresponding end of the lever 9 is also provided with an extension 28 provided with an extension 29 provided with a depending finger 29.

The opposite ends of the levers 10 and 11 are provided with extensions 30 and 31 provided with depending fingers 32 and 33. The fingers 24 and 25, 27 and 29, 32 and 33 depend through the orifices 6 and are offset inward at 34 as indicated in Fig. 6 so that the lower portion of the finger bears against the interior periphery of the hollow core centre. By tightening the nut 23 upon the bolt 21 the inner ends of the levers 8, 9, 10 and 11 are drawn inward forcing the opposite ends of the levers in the opposite direction and the depending fingers 24 and 25, 27 and 29, 32 and 33 carried thereby against the interior periphery of each of the exterior paper cores thereby positively holding them together. The bolt 21 is surrounded by a compression spring 35 so that when the nut 23 is loosened the levers will be carried outward so as to free the bundles and permit of the easy withdrawal of the retaining plates 2 and 3.

In Figs. 7 and 8 we have shown an alternative form of plate locking means. In this form the retaining plate is provided with depressed portions 36 in the form of an annular flange through which depend fingers

37 and 38 carrying blocks 39 and 40 having their inner faces provided with vertical grooves 41 and 42, the bases of which converge downward as indicated at 43 and 44 5 so as to coat with a wedge insertion 45.

By this means when the retaining plates are placed in position to hold the individual paper cores together to form a bundle the wedge 45 is driven in between the blocks 39 10 and 40 so as to spread them outward into contact with the diametrically opposite sides of the hollow core centre.

From this description it will be seen that we have devised a very simple means where- 15 by a series of paper cores such as are used for wrapping newsprint paper thereon for shipment may be bundled.

By our device the cores of paper are secured together in bundles each comprising 20 a definite number and therefore can be easily checked and the expense involved in handling them reduced. Also the cores themselves are safe from damage and loss and the expense incurred in bundling them with 25 twine or wire eliminated.

What we claim as our invention is:

1. A paper core bundling device comprising end plates provided with depressed portions fitting the hollow cores, means operated from the exterior of the plate and extending through the depressed portions for engaging the interior peripheries of the hollow cores, and holding locking means for carrying such engaging means simultaneously in and out of the engaging position.

2. A paper core bundling device comprising end plates having depressed portions adapted to fit the hollow core centres having openings in the bottom of the depressions, means extending through the openings having frictional locking engagement with the interior of the hollow core centre, and means for forcing the frictional locking en-

gaging means into engagement with the paper core.

3. A paper core bundling device comprising end plates having depressions adapted to fit the interior of the hollow cores, levers pivotally mounted upon the end plates at diametrically opposite points, fingers extending from the levers through the depressions of the end plates into the hollow cores, and means for drawing the levers inwards or outwards to carry the fingers in and out of engagement with the cores.

4. A paper core bundling device comprising end retaining plates having depressions adapted to fit into the hollow centres of the cores, a pair of levers pivotally mounted at diametrically opposite points upon the retaining plates, fingers carried at the ends of the levers adapted to extend through the depressed portions of the plates into the hollow core centres, means for pivotally connecting the free ends of the levers at each side of the centre together, and a draw bolt for drawing the pivoted ends of the levers inward.

5. A paper core bundling device comprising end retaining plates having depressions adapted to fit into the hollow centres of the cores, a pair of levers pivotally mounted at diametrically opposite points upon the retaining plates, fingers carried at the ends of the levers adapted to extend through the depressed portions of the plates into the hollow core centres, means for pivotally connecting the free ends of the levers at each side of the centre together, a draw bolt for drawing the pivoted ends of the levers inward, and resilient means for forcing the free ends of the levers outward when the draw bolt is released.

HAROLD ARTHUR MOREY,
CHRISTOPHER PHILIP ROBERTS WARREN.
